UNITED STATES PATENT OFFICE.

UGO P. COLOMBI AND JOSEPH ANANIA, OF MCKEESPORT, PENNSYLVANIA.

NIGHT LATCH.

Application filed February 19, 1925. Serial No. 10,403.

This invention relates to certain new and useful improvements in door locks and latches and has for its primary object to provide a lock wherein the latch bolt is constructed in a manner for cooperation with the keeper casing of the lock to prevent unauthorized tampering or sliding movement of the latch bolt for retracting the same to its releasing position.

10 A further object of the invention is to provide a lock for doors wherein a latch bolt having the usual beveled nose is of increased length to present a flat side face of the latch bolt rearwardly of the beveled nose in a position to extend across the meeting edges of a door and door frame and also span the meeting edges of the lock and keeper casings.

In locks of this general type, and more 20 specifically embodying the improvements above referred to, the latch bolt is usually constructed of a relatively soft material, such as brass and to eliminate the possibility of a person sinking an implement into the 25 latch bolt for purposes of sliding the same to its releasing position, the invention provides for the mounting of a steel plate on the side face of the latch bolt and spanning the space between the door frame and door.

30 With the above general objects in view and others that will become apparent as the nature of the invention is better understood, the same consists of the novel form, combination and arrangement of parts herein- 35 after more fully described, shown in the accompanying drawing and claimed.

In the drawing, wherein like reference characters designate corresponding parts throughout the same,

40 Figure 1 is a top plan view of a lock constructed in accordance with the present invention, the same being illustrated as mounted upon a door and door frame.

45 Figure 2 is a side elevational view, partly broken away and shown in section illustrating the increased length of the latch bolt and the steel wearing plate inserted in the face of the latch bolt disposed toward the outer side of the door and casing,

50 Figure 3 is a perspective view of the latch bolt, and

Figure 4 is a perspective view of the keeper casing for the latch bolt.

In the ordinary construction of a lock embodying a latch bolt, the inner edge of the

tapered nose of the latch bolt terminates at a point substantially flush with the forward edge of the lock casing so that the tapered nose of the latch bolt alone projects from the latch casing into the keeper casing for 60 the latch bolt and with the tapered side of the latch bolt nose disposed toward the outer side of a door and door casing with the result that a person inserting a thin implement between the edge of the door and casing 65 for engagement with the tapered side of the latch bolt nose may shift the latch bolt to its releasing position. To prevent unauthorized tampering with the latch bolt, the same as disclosed in this application is 70 of increased length so that a flat side of the latch bolt adjacent the beveled nose extends outwardly of the lock casing and spans the space between the lock and keeper casings 75 and the latch bolt being usually constructed of relatively soft material such as brass, a steel plate is inserted in the exposed side thereof so that an implement cannot be sunk into the latch bolt for sliding the same. To 80 compensate for the increased length of the latch bolt so that the same will be retracted during the closing movement of the door when the latch bolt engages the keeper casing, the latter is cut away to provide a clearance for the flat side of the latch bolt and to present the beveled nose for engagement 85 with an arcuate flange on the keeper casing.

Referring more in detail to the accompanying drawing, the lock is mounted upon a door 1 that moves to its closed position 90 adjacent the door frame 2 as shown in Fig. 2. The lock casing 3 of ordinary construction is secured to the door 1 and the keeper casing 4 for the latch bolt is secured to the door frame 2.

The latch bolt 5 shown in detail in Fig. 3 is of the usual spring pressed type with the forward beveled nose 6 and is of increased length as shown in Fig. 2 for spanning the space between the meeting walls 7 and 8 of the lock and keeper casings with the beveled nose 6 of the latch bolt entirely housed within the keeper casing 4 and spaced from the lock casing 3. The beveled nose of the latch bolt from the points —a— and —b— is entirely housed within the keeper casing and the side 9 of the latch bolt between the points —a— and —c— span the space between the walls 7 and 8 of the lock and keeper casings.

With the latch bolt 5 in the position shown in Fig. 2, a person forcing an implement between the door 1 and casing 2 and walls 7 and 8 of the lock and keeper casings presents 5 the implement for contact with the flat side 9 of the latch bolt and as the beveled nose 6 of the latch bolt from the points —a— to —b— is entirely removed from said space, unauthorized sliding movement of the latch bolt to its releasing position is prevented. The latch bolt being usually constructed of relatively soft material, such as brass or the like, it is important that the same be strengthened or reinforced, and to accomplish this result a steel plate 10 is countersunk within the flat side 9 of the latch bolt, as by a dove-tailed interlocking connection and may be wedgingly or otherwise retained therein as at 11. It will, therefore, be seen 15 that the relatively hard steel plate 10 spans the space between the walls 7 and 8 of the lock and keeper casings and unauthorized sliding movement of the latch bolt is prevented.

20 To compensate for the increased length of the latch bolt and permit the usual sliding movement thereof to its retracted position during closing movement of the door 1, the keeper casing 4 having the usual latch bolt receiving opening 12 in the forward wall 8 thereof is cutaway at the upper end as at 13 with the rear wall of the cutaway portion provided with an arcuate flange 14, while the top wall of the lock casing 3 carries a forwardly projecting flange 15 to be moved into engagement with the flange 14 to present a neat appearance at the inner side of the lock. When the door is moved to its closed position the flat face 9 of the latch bolt adjacent the beveled nose 6 will pass thru the cutaway portion 13 of the keeper casing and the rear edge —a— of the latch bolt nose 6 contacts the arcuate flange 14 to cause the bolt to be retracted into the lock casing against spring tension thereof and then be automatically projected into the keeper when the door 1 is fully closed.

While there is herein shown and described the preferred embodiment of the present invention, it is nevertheless to be understood 50 that minor changes may be made therein without departing from the spirit and scope of the invention as claimed.

What is claimed as new is:—

1. In a lock, lock and keeper casings, a 55 tensioned latch bolt slidable from the lock casing to the keeper casing, said latch bolt having a beveled nose with the rear end of the nose located in the keeper casing and located beyond the space between the lock 60 and keeper casings, and a steel insert set into the flat face of the latch bolt extending across the space between the two casings.

2. In a lock, lock and keeper casings, a 65 tensioned latch bolt slidable from the lock casing to the keeper casing, said latch bolt having a beveled nose with the rear end of the nose located in the keeper casing and located beyond the space between the lock 70 and keeper casings with a flat side of the latch bolt spanning the space between the casing, and a steel insert set into the flat face of the latch bolt extending across the space between the two casings.

3. In a lock, lock and keeper casings, a 75 tensioned latch bolt slidable from the lock casing to the keeper casing, said latch bolt having a beveled nose with the rear end of the nose located in the keeper casing and located beyond the space between the lock 80 and keeper casings with a flat side of the latch bolt spanning the space between the casing, a steel insert set into the flat face of the latch bolt extending across the space between the two casings, and the keeper cas- 85 ing having a cutaway portion providing a clearance for the extended latch bolt and an arcuate flange on the wall of the cutaway portion to engage the nose of the bolt for 90 automatic retraction thereof.

In testimony whereof we affix our signatures.

UGO P. COLOMBI.
JOSEPH ANANIA.
